UNITED STATES PATENT OFFICE.

TOLBERT F. CHEEK, OF NEW YORK, N. Y., ASSIGNOR TO WELTE-MIGNON CORPORATION, OF NEW YORK, N. Y., A CORPORATION OF NEW YORK.

MEANS TO OPERATE PIANO PEDAL MECHANISMS UNDER CONTROL OF A RECORD.

Application filed September 25, 1923. Serial No. 664,707.

It will be understood that record controlled piano playing mechanisms of the type herein referred to as "cabinet piano players" or "outside player" is that type in which the mechanism for playing the piano is mounted in a cabinet or casing outside of and separate from the piano itself and mounted to be moved to the piano to operate the latter and to be moved away from the piano when the piano is to be played manually, instead of under control of a record. These player mechanisms—i. e. of the outside or cabinet type—have always been provided with projecting levers or the like which are mounted in the casing or cabinet and operate directly upon the pedals of the piano, which as is well known are always arranged close to the floor. Accordingly, it has been the practice to encase the playing mechanism in a cabinet the body of which extends almost to the floor. Such a cabinet presents a "boxy" and inartistic and displeasing appearance, and is insanitary.

One of the important purposes of the present invention is to provide piano playing mechanisms of the outside or cabinet type with means whereby the sostenuto, or sustaining, and soft pedal mechanisms of the piano may be operated under control of a record without necessitating that the bottom of the cabinet be close to the floor to inclose means to operate upon the pedals themselves, thereby enabling the cabinet to be mounted on legs which sustain it well above the floor of the room, and consequently to be more sanitary and to present a more artistic and pleasing effect.

Other purposes of the invention have to do with the provision of most practicable means for operating the pedal mechanisms under control of mechanism contained in the casing of an outside or cabinet piano player which is mounted to be movable into and out of operative relation with the piano. These purposes will be readily understood from the following description of the preferred embodiment of the invention illustrated in the accompanying drawings, wherein like characters of reference denote corresponding parts in both of the figures and in which:

Fig. 1 is a side view of the forward part of a grand piano and of a cabinet player in operative relation therewith, mainly in ele-

vation but with certain parts broken away and other parts in section to disclose elements necessary to an understanding of the present invention, and with all other elements of the piano and player omitted.

Fig. 2 is a diagrammatic representation particularly showing the parts of the player mechanism and piano germane to the present invention.

Pianos, both of the upright and grand type, are universally provided with a damper, as A, for each string, or set of strings giving forth the same tone; and with a connection from each of said dampers to the corresponding piano key, each of which connections usually includes a pivoted member, as a, which engages the end of the corresponding damper rod a'. Pianos, moreover, are universally provided with hammers, one of which is shown and is marked B, whose number corresponds with the number of strings, or sets of strings giving forth the same tone. These hammers are connected with the keys of the piano, respectively. The correlation of the parts is such that when any key of a piano is struck the corresponding hammer is moved to strike the string, or set of strings, upon which it operates and simultaneously therewith the corresponding damper is raised from said string or set of strings, through the medium of the members of the piano action by which each key is connected with the corresponding hammer and damper. A particular form of said action is not essential to the present invention and as many suitable constructions are well known, I have considered it to be unnecessary to illustrate or to set forth in detail, any of the same herein, except as to those elements which are most intimately connected with, or form parts of the pedal mechanisms, and as to these elements, I have illustrated them in connection with a "grand" piano, although my invention is equally applicable to pianos of the "upright" type.

These pedal mechanisms universally include a sostenuto or "sustaining" pedal, as C, and a soft pedal, as D. The loud or sustaining pedal has suitable connection by means of elements forming parts of the sostenuto pedal mechanism, with a member, as damper rail C' which is common to all the dampers, and which member is operated to move all

the dampers away from their strings when the pedal is depressed and to hold them in that position until the pressure on the pedal has been removed, thereby giving sustained effects to all notes which are being sounded while said pedal is thus depressed, it being understood that the dampers unless thus held will fall gravitationally into re-engagement with the corresponding strings as soon as the pressure on the corresponding piano key is removed. The damper rail is shown as being pivoted at C' to enable it to swing about a horizontal axis and operatively related to the lever a and it will be understood that in practice it engages the entire series of said levers in order that it may move and hold the dampers away from their strings. The illustrated connection between it and the sustaining pedal C includes a lever C'' which is pivoted at one of its ends, c'', so that it may swing upon a horizontal axis from its said end, and has its opposite end in contact with, but not necessarily secured to, the upper end of a rod, c², which is pivoted at its lower end to the inner end of the loud pedal. The intermediate portion of the lever C carries the damper rail rod c³, whose upper end supports the damper rail C'. The soft pedal D in practice is variously connected with appropriate parts of the piano mechanism to bring about the soft effects which its operation is intended to accomplish. In some instances, it operates to interpose a muffler between the hammer and string; in other instances it operates to shift the entire series of hammers nearer to the strings whereby their stroke is shortened; in still other instances it shifts the hammers laterally—sometimes also shifting the keys as well as the hammers—so that each hammer strikes one string only in producing the tone. My invention is not particularly concerned with which of these different means the soft pedal is correlated to produce its purpose. In other words, it is applicable to any of the same, although I have herein illustrated it as applied to that type in which the hammers B' are moved nearer to the strings, the drawing showing a vertically movable rail D', which in practice, as will be readily understood, is common to the several hammers, and is raised when the soft pedal is depressed, it being connected with the free end of a lever D'' by a rod d' and said free end of the lever being connected with the inner end of the soft pedal D by a rod d''.

As already brought out herein, the parts thus far set forth are merely exemplary of pedal mechanisms and associated parts commonly embodied in pianos as now constructed and they are only illustrated herein in order that my means for operating said pedal mechanisms may be more completely understood. My said means includes two

power members, herein illustrated as pneumatics E and F, for applying to said pedal mechanisms, respectively, the power which operates the same under control of a record. These power members are outside the player and, preferably, are carried by the piano itself and they are so correlated with the respective pedal mechanisms that they do not interfere with the foot operation of the pedals when the player is being played by hand. It is advantageous and, therefore, preferred that they, apply their power to elements of the pedal mechanisms other than the pedals themselves, so that they do not depend for their operation upon any operation of said pedals when the piano is being played under control of a record. They are here illustrated, for exemplary purposes, as being arranged to apply their power to the levers C'' and D'', respectively. 80

As already stated they are preferably carried by the piano, while the mechanism which controls their operation under control of a record is mounted in a casing or cabinet marked G, outside of the piano itself and which is movable relatively to the piano and power members. This cabinet G also contains usual or any suitable mechanism, not necessary to disclose, for operating the piano keys under control of a record, including strike levers, g, protruding from the back of the casing G to engage the piano keys, respectively, when the player is in operative relation with the piano. As these cabinets when in operative relation with the piano interfere with the manual playing of the latter, and hence it is customary to move them away from the piano when the latter is to be played by hand, it is part of my invention to provide connections between the power members E and F and the player, of a nature which will permit the required movement of the latter to and away from the piano and power members. This is well accomplished in the herein exemplified form of the invention by the use of couplings, as 38, 42, of any suitable detachable nature in the connections between the power members and the control means for said power members in the cabinet. 100

Record controlled mechanisms for playing pianos now commonly used are of a pneumatic nature and have a tracker bar, as I, provided with suitable atmospheric ducts, as i, through which air is admitted under control of a record, not shown, to operate pneumatic means which in turn control the operation of the striker levers g, the present practice also preferring that these pneumatic mechanisms operate upon the exhaust principle; that is to say, that they include means for producing exhaust tension within the mechanism and elements by which the pneumatics are controllable subjected to such tension and to air at atmospheric pressure in the 110 120 125 130

operations of the pneumatics. I, too, prefer to employ pneumatic mechanisms and those which operate on the exhaust principle and, therefore, have illustrated and will describe in detail an embodiment of my invention of a pneumatic nature and operating upon the exhaust principle, but would have it understood that the invention in certain of its broad aspects as defined by appended claims 10 is not restricted thereto.

The illustrated power members E and F are bellows which will collapse when their interiors are subjected to air at a pressure less than that of the atmosphere and will 15 expand when their interiors are again opened to air at atmospheric pressure, it being understood, of course, that the exteriors of such bellows are always subjected to air at atmospheric pressure and that they are commonly provided with springs which are connected with the movable members thereof and are arranged to move said members outward when the pressure within the bellows is such with relation to the pressure without 20 the bellows that the springs may act to accomplish the purpose referred to.

The pneumatic control mechanism which I prefer to use includes a double valve, comprising members 10—11, to control the air tensions within the bellows E and a like double valve, comprising members 12—13', to control the air tensions within the bellows F. These double valves are pneumatically operated preferably by the means hereinafter 25 described, under control of a record which, as will be readily understood, is provided for this purpose with perforations additional to those which control the operations of the striker levers, the mechanism including ducts 13 and 14 which extend from special tracker apertures 15 and 16 to be opened to the atmosphere at predetermined times by the registration of the additional record-perforations therewith. A double locking or releasing valve comprising members 17 and 18 is provided for the double valves 10—11, and a double locking or releasing valve comprising members 19 and 20 is provided for the double valves 12—13'. These locking or releasing valves (hereinafter called locking valves for brevity's sake) are similarly controlled by the record which for this purpose has additional perforations to register with special tracker apertures 21 and 22 to thereby 30 open to the atmosphere special control ducts 23 and 24, respectively, for the releasing operation.

The several valves referred to are arranged in a box or unit which is constructed 35 to provide a chamber 25 for the double valves 10—11; a similar chamber 26 for the double valves 12—13'; chambers 27 and 28 for the respective locking valves 17—18 and 19—20; chambers 29 and 30 into which the ducts 13 and 14 open; chambers 31 and 32

into which the ducts 23 and 24 open; and a common conduit 33 which is constantly under exhaust tension produced by the means, not shown, employed to produce such tension throughout the mechanism and with 70 which it has connection through a duct 34.

The chamber 25 is provided with an exhaust port 35 to the conduit 33 and with an atmospheric port 36 and has communication with the interior of the power pneumatic E 75 through a duct which comprises two members 37 and 37' and a suitable coupling 38 by which said members are detachably connected with each other. The chamber 26 similarly is provided with an exhaust port, 39, 80 and an atmospheric port, 40, and has communication with the interior of the power pneumatic F through a duct which comprises two members 41 and 41' detachably connected with each other by a suitable coupling, 42. The chambers 27 and 28 have communication with the suction conduit through exhaust ports 43 and 44, respectively, and with the atmosphere through ports 45 and 46, respectively. 90

The valve members 10 and 11 are mounted on a stem 47 one of whose ends is operatively related to a membrane 48 whose opposite sides are subjected to the air tensions in the chamber 29 and suction conduit 33, and the other of whose ends is operatively related to a membrane 49 whose opposite sides are subjected to the air tensions in chambers 50 and 51. The chamber 51 has communication with the chamber 25 through a channel 52 100 so that the tension of the air therein is always the same as that in the chamber 25, and the chamber 50 has communication with the chamber 27 through a channel 53 so that the air tensions in these two chambers is always 105 the same. Similarly the valve members 12—13' are mounted on a stem 54 one of whose ends is operatively related to a membrane 55 whose opposite sides are subjected to the air tensions in the chamber 30 and suction conduit 33, and the other of whose ends is operatively related to a membrane 56 one of whose sides is subjected to the air tension in a chamber 57 which has communication with the chamber 26 through a channel 58, 110 and the other of whose sides is subjected to the air tension in a chamber 59 which has communication with the chamber 28 through a channel 60.

The suction conduit 33 has communication 120 with the chambers 29, 30, 31 and 32 through bleed holes 61, 62, 63 and 64, respectively.

It will thus be seen that the correlation of the parts in this illustrated embodiment of the invention is such that when the player mechanism is in operation and the conduit 33 is thereby under suction, but with all of the tracker apertures 15, 16, 21 and 22 closed, the air in the ducts 13, 14, 23 and 24, and in chambers 29, 30, 31 and 32 will be rare- 125 130

fied, through the bleed holes 61, 62, 63 and 64 and the valve members 10—11 and 12—13' will be in such relation to the respective ports 35—36 and 39—40 that the suction ports 35 and 39 will be closed and the atmospheric ports 36 and 40 will be open, and similarly the valve members 17—18 and 19—20 will be in such relation to the ports 43—45 and 44—46 that the suction ports 43 and 44 will be closed and the atmospheric ports 45, 46 will be open. Hence, the power member E at this time will be expanded, as its interior is in communication with the atmosphere through port 36, chamber 25 and duct members 37, 37', and the power member F also will be expanded as its interior likewise is in communication with the atmosphere through port 40, chamber 26 and duct members 41, 41'. At the same time, the chambers 50 and 51 will be under atmospheric pressure the latter chamber (51) through channel 52 leading thereto from chamber 25, and chamber 50 through channel 53, chamber 27 and port 45. Similarly, the chambers 57 and 59 will both be under atmospheric pressure—chamber 57 through channel 58, chamber 26 and port 40, and chamber 59 through channel 60, chamber 28 and port 46.

If now the duct 13 be opened to the atmosphere by the registration of a record-perforation with the tracker aperture 15, air at atmospheric pressure will instantly be admitted to the chamber 29, thereby distending membrane 48 and raising the valve-members 10—11 whereupon the atmospheric port 36 will be closed and suction port 35 will be opened. The power pneumatic E being thus placed under suction will collapse, its movable member acting upon the lever C'', through its projection e', to raise the damper rail C' and thereby lift all the dampers from the strings. At the same time, the closing of the atmospheric port 36 and the opening of the suction port 35 will place the chamber 51 under suction and as the air in chamber 50 is at this time atmospheric pressure through channel 53, chamber 27 and port 45 it will follow that the valves 10 and 11 will be maintained in the position to which they were moved as a consequence of the opening of duct 13, until the tension of the air in chamber 50 is reduced, by the opening of duct 23 under control of the record. This opening of the duct 23, will cause air at atmospheric pressure to be admitted to chamber 31, thereby distending membrane 56 and causing valve members 17—18 to be raised and to close atmosphere port 45 and open suction port 43, respectively. The air in chamber 50 is thereby attenuated through port 43, chamber 27 and channel 53, whereupon the tensions of the air in chambers 50 and 51 being thus relatively such that the pressures on

opposite sides of the membrane 49 will be equalized as are also the tensions of the air exerted on opposite sides of the membrane 48—the valve members 10, 11 will fall, thereby instantly opening the chamber 25 to the atmosphere. Air at atmospheric pressure being thus admitted through ducts 37, 37' to power pneumatic E will cause the latter to be expanded, whereupon the damper rail will fall, so that it no longer holds any of the dampers away from the strings. These parts are now ready for a repetition of the operation just described, it being further noted that at this time the air in chambers 29 and 31 and ducts 13 and 23 will be rarefied through the bleed holes 61 and 63 so that the mechanism will be instantly responsive to the admission of air at atmospheric pressure to the ducts 13 and 23.

The operation of the parts correlated with the power pneumatic F for moving the hammer rail and hammers nearer to the strings and for returning the same to its normal position is substantially the same as that just set forth with relation to the power pneumatic E: the opening of the duct 14 by the registration of a record-perforation with the tracker aperture 16, admitting air at atmospheric pressure to the chamber 30, thereby causing valve members 12, 13' to be moved to open suction port 39 and close atmospheric port 40, thereby placing the interior of pneumatic F and also the chamber 57 under exhaust tension, causing the pneumatic F to collapse and through its movable board f and projection f' to raise the hammer rail D'', and at the same time causing the atmospheric pressure in chamber 59 to become effective to hold the valve members 12, 13' in their said position after duct 14 has been closed and until duct 22 has been opened by the registration of a record perforation with the tracker aperture 22. When the latter occurs, that is to say when the tracker aperture 22 has been opened, air at atmospheric pressure, will, of course, be admitted to the chamber 32, thereby distending membrane 55 and moving valve members 20 and 19 to open suction port 44 and close atmospheric port 46, so that chamber 59 will now be exhausted and valve members 12, 13' may return to their former positions, closing suction port 36 and opening atmospheric port 40, thereby placing chamber 57 and the interior of the power pneumatic F in communication with the atmosphere, distending said pneumatic and lowering the hammer rail, and leaving all of the parts in position for a repetition of the before mentioned operation.

When it is desired to play the piano by hand, and for this reason, or for any other reason, the cabinet must be removed from its operative relation to said piano it is only necessary to break the connection between

the power pneumatics E and F and the controlling means therefor in the cabinet and this may be conveniently and expeditiously done in this exemplification of the 5 invention by the simple operation of uncoupling the duct members 37 and 37' and duct members 41 and 41' from each other.

Having thus described my invention and set forth in detail the preferred embodiment thereof, what I believe to be new and desire to secure by Letters Patent, and what I, therefore, claim is:—

1. A piano player of the outside or cabinet type, movable into and out of operative 15 relation with a piano and including a casing, a series of strike levers movable with the casing and into position to operate directly upon the keys of a piano, a tracker and pedal control means operative under control of a record: in combination with power 20 members arranged outside the player, connections between said power members and pedal control means and means under control of the power members to operate the 25 pedal mechanisms of the piano.

2. A piano player of the outside or cabinet type, movable into and out of operative 30 relation with a piano and including a casing, a series of strike levers movable with the casing and into position to operate directly upon the keys of a piano, and a tracker; in combination with means to operate the pedal mechanisms of the piano under control of a record, including pneumatically 35 operative pedal control valves carried by the player and having connection with the tracker, power members outside the player, connections, having separable members, between the pedal control valves and the power members, and members under control 40 of the power members to connect the latter with the pedal mechanisms of the piano.

3. Means to operate the pedal mechanisms 45 of a piano under control of a record, including a player of the outside or cabinet type having, in addition to the mechanism under control of a record to operate the keys of the piano, pneumatically operable valves 50 also under control of the record, power members outside the player, connections between said valves and the power members, respectively, members under control of the power members to connect the latter with the pedal mechanisms of the piano, locking 55 valves carried by the player and under control of the record, and connections between the locking valves and the first mentioned valves, respectively.

4. The combination with a piano having 60 a keyboard and pedal mechanisms, of a player of the outside or cabinet type having record controlled strike levers to operate directly upon the keys of the piano and 65 also having record controlled pedal control

means, and power members arranged outside the player and operatively related to said pedal mechanisms and connected with the control means of the player to be operative under control of the latter. 70

5. The combination with a piano having a keyboard and pedal mechanisms, including pedals, of a player of the outside or cabinet type having record controlled strike levers to operate directly upon the keys of the piano, and also having record controlled pedal control means, and power members arranged outside the player and operatively related to said pedal mechanisms to operate the same independently of the pedals, and 75 connections between said power members and the pedal control means of the player to cause the power members to be operated under control of said means.

6. The combination with a piano having 80 a keyboard and pedal mechanisms, and a player of the outside or cabinet type, having record controlled strike levers to operate directly upon the keys of the piano, and also having record controlled pedal control valves, of power pneumatics arranged 85 outside the player and operatively related to said pedal mechanisms and having connection with said control valves, to operate the pedal mechanisms under control of the 90 control valves in the player.

7. The combination with a piano having 95 pedal mechanisms, and power members having connection with said pedal mechanisms to operate the same to produce pedal effects, of a player of the outside or cabinet type movable into and out of operative relation with the piano and relatively to the power members and provided with control means under control of a record to control the 100 power members.

8. The combination with a piano having 105 pedal mechanisms and power members having connection with said pedal mechanisms to operate the same to produce pedal effects, of a player of the outside or cabinet type 110 movable into and out of operative relation with the piano and relatively to the power members, and means forming part of the player to control the power members, said means being under control of a record and including locking members to control the action of said means with relation to the power members.

9. The combination with a piano having 115 loud and soft pedal mechanisms, and power pneumatics, respectively, having connection with said pedal mechanisms to operate the same, of a player of the outside or cabinet type, movable into and out of operative relation with the piano and relatively to the power members, the player including a tracker, control valves having connection with the tracker, means to connect the control valves to the power members, respec- 125 130

tively, and locking valves having connection with the tracker and with the control valves.

10. The combination with a piano having 5 loud and soft pedal mechanisms, including pedals, and power pneumatics, respectively, having connection with said pedal mechanisms to operate the same independently of the pedals, of a player of the outside or 10 cabinet type, movable into and out of operative relation with the piano and relatively to the power members, the player including a tracker, control valves having connection with the tracker, means to connect the control 15 valves to the power members, respectively, and locking valves having connection with the tracker and with the control valves, the connection between the control valve and the power members including dis- 20 connectible elements.

11. In combination: a piano having 25 dampers, hammers, a keyboard and pedal mechanisms, including pedals; a player of the outside or cabinet type movable relatively to the piano and having record controlled devices to engage and operate the piano keys when the player is in position to operate the piano; power members for the pedal mechanisms, respectively, mount- 30

ed outside the player and operative upon 30 the pedal mechanisms independently of the pedals; means carried by the player to control the power members, respectively; and operative connections between the control means and power members permitting relative movement of the player and power members. 35

12. In combination: a piano having dampers, hammers, a keyboard and pedal mechanisms, including pedals; a player of the 40 outside or cabinet type movable relatively to the piano and having record controlled devices to engage and operate the piano keys when the player is in position to operate the piano; power members for the pedal 45 mechanisms, respectively, mounted outside the player and operative upon the pedal mechanisms independently of the pedals; means carried by the player to control the power members, respectively, including record controlled control valves and record controlled locking valves for the control valves; and operative connections between the control means and power members permitting relative movement of the player and 50 power members. 55

In testimony whereof I affix my signature.
TOLBERT F. CHEEK.
